UNITED STATES PATENT OFFICE.

MAURICE COURTEAU, OF PARIS, FRANCE, ASSIGNOR TO FRANCIS MOREAU, OF HANOI, TONKIN.

DOOR-FASTENING DEVICE.

Application filed September 19, 1925, Serial No. 57,397, and in France October 1, 1924.

My invention relates to a device for the fastening of doors which open to the outside, such as the doors of railway or of motor vehicles, and the like. By the use of 5 my said fastening device I am enabled to prevent all spontaneous opening of the door whereby all accidents due to such opening will be avoided.

My said device comprises fastening elements which consist firstly of an inner door handle which may be turned down behind the door post and secondly of an outer latch which engages in a hook-shaped keeper and is automatically held in place 15 by a spring-mounted and hand controlled fastening catch.

In a modification, the said latch is mounted directly upon the spindle of the handles. The hook-shaped keeper is eliminated, and 20 is replaced by a keeper which is inserted into the door post, and projects therefrom only to a moderate extent. This projecting part has the form of a ramp, and it serves to guide the first part of the movement 25 of the inner handle and of the door latch when the door is closed. The catch which serves to hold the said latch in the closing position, is disposed in the interior of the said keeper.

30 Two constructional forms of the invention are shown by way of example in the accompanying drawings.

Fig. 1 is an elevational view of the exterior of the device which is placed in position, with parts broken away.

Fig. 2 is a vertical section on the line II—II of Fig. 1.

Fig. 3 is a horizontal section on the line III—III of Fig. 2.

40 Fig. 4 is a view similar to Fig. 1 but showing a modification.

Fig. 5 is a vertical section on the line V—V of Fig. 4.

Fig. 6 a vertical section on the line 45 VI—VI of Fig. 4.

In Figures 1 to 3, 4 is the main body of the door and 5 the door post, or otherwise stated, the vehicle body. The fastening device according to the invention comprises 50 a shaft or spindle 6 which traverses the main body of the door 4 and is terminated at one end by an outer handle 7 and at the other end by an inner handle 8 situated within the vehicle. On the outer side, the 55 spindle 6 traverses a casing 9 secured to the

door by screws 10 and containing an arm 11 secured to the spindle 6 and pulled downwardly by a spring 12 disposed in the main body of the door and attached at the other end to a suitable hook 13.

60 The arm 11 is connected by the link 14 to a pivoted door latch 15 mounted on an axle 16 between the walls of the casing 9 and extending outwardly from the latter on the side next the door post 5. A hook-shaped keeper 17 is secured to the body 5 by the screws 18 and is placed at the same level as the latch 15, so that the latter may engage the said keeper for closing purposes.

Above the cut-out part of the said hooked keeper is mounted a catch 19 secured to a shaft or spindle 20 which traverses the door post 5 and is controlled by the spring 21 (Fig. 3) in such manner that the said catch will tend to assume a vertical position. At 70 the end of the spindle 20, and on the inside of the vehicle, is mounted an arm 22 provided with a lug 23; on the outside of the vehicle there is provided a similar lug 24 which is formed integral with the catch 19. 80

The said device is completed by a fastening element 25 contained in the casing 9 of the door and secured to a spindle 26 traversing the said door. By the rotation of spindle 26, the element 25 can be brought against 85 a flat part or seat 27 of the latch 15 whereby all motion of said latch will be prevented. The element 25 can be rotated either from the inside or the outside of the vehicle by means of a special key which may be engaged in an eccentric recess 28 formed in the respective ends of the axis 26. The positions of holding or release of the element 25 are determined by a spring strip 29 which abuts against the flat parts of the said element, said parts having suitable directions.

90 Upon the said door post is mounted a plate 30 which forms an acute angle with the inner face of the vehicle body and an obtuse angle with its outer face, this in fact coinciding with the known arrangement of vehicle doors. It should be noted that I dispose the inner handle 8 so that it extends outwardly beyond the door, in order that it may positively control the closing 105 of the door.

110 In fact, if the door is open and one pushes upon it in order to close it, the inner handle 8 will encounter the end of the hooked keeper 17 whose shape is so designed as to

raise the said handle, which thus slides upon the said keeper and engages the interior of the door frame, by friction contact with the plate 30; the handle continues to rise, and it 5 then drops behind the door post under the action of the spring 12.

The latch 15 engages the said keeper and descends at the same time as the handle 8, and then drops into the cut-out part of the 10 said keeper, pushing aside the catch 19 and then allowing it to resume its vertical position above the cut-out part. It will be observed that in this position of the parts, the door is held closed both by the internal 15 handle 8 which is brought down at the rear of the door post 5 and by the latch 15 which is engaged in the hook keeper 17 and is held by the catch 19.

To open the door from the inside or the 20 outside, it will thus be necessary, before operating the handles, to separate the catch 19 from the hook 17 by pushing either of the lugs 23, 24 in the proper direction; when the said catch is disengaged, it is simply necessary to operate one of the handles 25 7 or 8 in order to raise both the handle 8 and the latch 15, so that the door may be opened.

Obviously, this series of movements can 30 not take place spontaneously, so that my said device will obviate all danger of accidents which might be caused by opening of the door.

The modification which is shown in Figs. 35 4 to 6 comprises a metallic casing 40 which is inserted into the wood of the door 41 and is secured by the screws 42; said casing maintains the spindle 43 of the door handles, whereof the outer handle 44 is of known 40 form and the inner handle 45 is disposed as in the preceding case so as to descend at the interior behind the door post and thus serve as a closing element.

The spindle 43 is controlled by a spring 45 46 which surrounds the said spindle and whereof one end is engaged therewith and the other end with the casing 40. To the spindle 43 is keyed the latch 47 which extends from the said casing outwardly beyond the door and is adapted to enter a keeper 48 disposed in the wood of the door post. The said keeper has only a small portion 50 49 extending outwardly, it being adapted to start the necessary movements of the handle 45 and of the latch 47 when closing the door.

Within the keeper 48 is disposed a holding latch 50 which is secured to a spindle 51 extending entirely through the door post and having mounted at each end a push piece or lug 52. The said spindle is brought back by a spring 53 which tends to maintain the catch 50 in vertical position, i. e. in the position in which the latch 47 is held 55 in the keeper 48.

The fastening element in this form comprises a holding arm 54 contained in the casing 40 and secured to a spindle 55 which has mounted at each end an eccentric socket such as 56 into which may be inserted a 70 special key whereby the spindle 55 may be placed in one of the two positions corresponding respectively to the locking of the device or to the complete release of its parts. A spring strip 57 is provided in order to 75 maintain the arm 54 in either of the aforesaid positions.

The said modification operates in the same manner as the preceding device, so that no further description of the same will be necessary. But it should be remarked that in the present case the catch, the latch, and the keeper are no longer visible from the exterior, thus providing a vehicle body comprising no unsightly projections. Also, the 80 said latch is directly mounted upon the axis of the door handles, thus eliminating two cumbersome elements comprised in the preceding device.

In addition to the consideration of safety, 90 which is the chief object of the invention, my said device has other advantages, among which may be mentioned the following:—

The said device is very substantial, this being due to the simple character of the 95 elements, whereby a most reliable operation is assured.

Due to the disposition of all the elements on the outer edge of the door, this latter may be fitted with all suitable means for operating the windows, but without cutting into the wood of the door in such manner as to weaken the same.

I employ for the rearward control of the several elements of the device, a spiral 100 105 spring 12 which is of a straight and substantial type, instead of the known volute springs which are of a fragile nature.

Obviously, my said invention is applicable with equal facility to doors which open to 110 the front or to the rear, and to the right or left, and in each particular case I may modify the said apparatus in detail without departing from the principle of the invention.

I claim as my invention:

1. A door fastener, comprising a casing for attachment to a door; a keeper for attachment to the door post; a latch mounted in the casing for engagement with the keeper; a spindle for operating the latch passing transversely through said casing and provided at its ends with inner and outer handles located on opposite sides of the door, the inner handle normally projecting beyond the door edge so that its path of movement with the door intersects the keeper; and guide means on said keeper to engage the projecting portion of said handle and move it out of line with the keeper so as to 120 125 130

enable it to pass by the keeper as the door completes its closing movement; said handle finally disengaging said means when the door reaches its fully-closed position, whereby it is enabled to automatically assume a position in which it projects across the door post.

2. A door fastener, comprising a casing for attachment to a door; a keeper for attachment to the door post; a latch mounted in the casing for engagement with the keeper; a spindle for operating the latch passing transversely through said casing and provided at its ends with inner and outer handles located on opposite sides of the door,

the inner handle normally projecting beyond the door edge so that its path of movement with the door intersects the keeper; and guide means on said keeper to engage the projecting portion of said handle and lift it out of line with the keeper so as to enable it to pass by the latter as the door completes its closing movement; said handle finally dropping after it has passed by said means when the door reaches its fully-closed position, whereby it is enabled to automatically assume a position in which it projects across the door post.

In testimony whereof I affix my signature.
MAURICE COURTEAU.
